UNITED STATES PATENT OFFICE.

STEPHEN JOSEPH BRUNE, OF THE UNITED STATES NAVY.

COIN-HANDLING APPARATUS.

1,396,923.

Specification of Letters Patent. Patented Nov. 15, 1921.

Application filed March 9, 1920. Serial No. 364,503.

To all whom it may concern:

Be it known that I, STEPHEN JOSEPH BRUNE, a lieutenant in the United States Navy, have invented certain new and useful 5 Improvements in Coin-Handling Apparatus, of which the following is a specification.

My invention relates to improvements in coin handling apparatus, and it consists in 10 the constructions, combinations and arrangements herein described and claimed.

One of the foremost objects of the invention is to provide an improved method of handling large quantities of coins, a preferably rectangular or square box being used 15 to hold the coin, the box being so arranged that stacks of coin can readily be shoved out for distribution in the manner fully described below.

20 A further object of the invention is to provide a square box for holding stacks of coins of any given denomination, the lid of the box being sealed and having the amount contained thereby indicated in some convenient place, numbers of such boxes being 25 capable of being piled one on top of the other if they are intact, all danger of breaking, as in the case of cloth bags, being avoided by the use of such boxes, and the 30 officer in charge of the money being enabled to strike a balance very easily by calculating the total contents of all boxes left intact in addition to the loose money at hand. If the boxes are not intact, the 35 flanges may be rested on inclined shelves or slides made for the purpose, the object of inclining the slides being to make the coin stacks settle at the closed end and adjacent side and so stay in place.

40 A further object of the invention is to provide an improved money container consisting of a box as described above, with numerical designations along one edge indicating the amount of money in transverse 45 stacks of coin, the farthest end of the box being removable when the box is in use, whereupon the remaining amount of coin can be quickly ascertained by simply glancing at the designation along said edge, 50 thus making it additionally easy to strike

a balance by avoiding the necessity of having to count all of the stacks of coin in order to see how much is left in the balance.

A further object of the invention is to provide novel means capable of being carried out in various forms, for keeping the stacks of coin together, that is to say, to prevent the top coin of one stack from sliding onto another stack in case that stack should be lower by reason of the coins therein being worn to a greater degree than those in the higher stack. 55

A further object of the invention is to provide a plurality of graduated scrapers or coin removers, by the use of which any 60 number of stacks of coin in one row can be slid out of the open end of the box when the box is placed in the disbursing position. 65

A further object of the invention is to provide a coin container as described above, 70 which is so arranged that the individual transverse rows can be inspected in order to see whether the piles of coin are intact to the bottom of the box.

Other objects and advantages will appear 75 in the following specification, reference being had to the accompanying drawings, in which:—

Figure 1 is a perspective view of a metal coin container constructed in accordance 80 with my invention, the lid being screwed on and places for seals being indicated,

Fig. 2 is a side elevation of the box showing 85 it in place on an independent stand from which position the coin is disbursed,

Fig. 3 is a detail section taken substantially on the line 3—3 of Fig. 1, showing how the securing screw is driven flush with the surface of the top so that other boxes 90 may more readily be piled on,

Fig. 4 is a detail sectional view taken substantially on the line 4—4 of Fig. 1 and illustrating the arrangement of the removable end, and various kinds of spacers,

Fig. 5 is a detail side elevation showing 95 where one of the seals is applied on the edges of the top and flange,

Fig. 6 is a perspective view of the box with the lid partially raised, showing a thick mat in use on top of the stacks of coin 100

for the purpose of keeping the coins in place,

Fig. 7 is a detail perspective view of a portion of the box illustrating another method of keeping the coins in place,

Fig. 8 is a detail view illustrating how one of the scrapers or removers is employed to successively shove rows of coins aside so that the next row may be inspected for intactness,

Fig. 9 is a detail perspective view of two stacks of coin illustrating the preferred way of separating them,

Fig. 10 is a detail sectional view illustrating the use of a center bolt to keep the bottom of the box from sagging,

Fig. 11 is a perspective view illustrating the use of an extension tray in connection with the coin box, also illustrating the use of one of the graduated coin removers, and

Figs. 12, 13, 14 and 15 are detail views illustrating various forms of the scrapers or coin removers.

25 *The coin-container*

comprises a box 1 which is preferably made of metal so that a flange 2 may be provided around three sides, the fourth side being left open, as at 3, for the purpose of admitting the removable plate 4. This plate has a flange 5, and when fitted in place as shown in Fig. 1, completes the box.

A lid 5^a is screwed down on the flanges of the box as at 6, with screws the heads of which are flush with the top or lid, so that when a number of the boxes are piled one on top of the other, the screws will form no obstructions to the easy piling of the boxes. In cases where great quantities of coin are handled daily, it is far easier to manipulate boxes containing the coin, than it is to manipulate the ordinary bags which are now customarily used. Such bags cannot easily be piled, and furthermore they are liable to wearing out in places so that it frequently happens that the coins are lost. The metal box does not wear out, and any number of the boxes can be banked up, making it easy to dispose of great quantities of coin in a 50 relatively small space.

A hole 7 is bored in from one or more of the edges of the flanges, to be filled with sealing wax 8 and stamped with an appropriate legend to indicate that the box is full of coin and has passed inspection. Fig. 5 shows the seal in detail. Although not illustrated, it is easily seen that the boxes can be sealed with wire as well as wax. The removable side or front 4, referred to above, carries a plurality of pins 9 (or screws if necessary) on the bottom edge, to fit into similar apertures 10 in the bottom of the box so as to effect a firm connection when the side is put in place and secured. This side

is taken out when the coin is to be disbursed 65 as illustrated for example in Fig. 11 and as described more fully below.

The manner of packing the coin

may be carried out in any one of a number of 70 different ways, but that method illustrated in Figs. 9 and 11 is preferable to any of the others because of its simplicity, cheapness and effectiveness.

Assume that we are packing coins of any 75 particular denomination into the box 1. A stack is set in place in one corner, the end of a rather long ribbon of paper 11 being partially wrapped around that stack and so disposed that when the next stack is set 80 in place the paper can be partly wrapped the second stack also.

The effect is that of simply twining or threading a ribbon of paper, first on one side, then on the other, and so on, of all of 85 the stacks of coin, completely across the box. The ribbon should be a little wider than the stack is high so that when the lid is pressed down, the little upstanding edge of paper will be crushed over the top of the stack of 90 coin, as at 12 in Fig. 9, and thus prevent the top coin of a stack which may be a little higher than its companion stacks, from sliding over onto the lower stack and thus making that stack contain a greater value of 95 coins than it should.

Stiff paper separators 13, 14 are placed between the rows of coin, the separator 13 being higher than the one 14 for the purpose of facilitating the introduction of the 100 edge of the scraper 15, which is employed when it is desired to inspect the various rows of coin for intactness to the bottom. To illustrate: In Fig. 8 the scraper or remover 15, which is the equivalent of either one 105 illustrated in Figs. 12 and 15, was introduced between the separators 13 and 14, and all of the rows of coins moved backwardly so as to leave a sufficient space, as shown. The inspector can now readily glance down 110 in the direction of the arrow, the separator 14 having fallen over, or failing to fall over can be moved aside, so that he can readily see whether all of the rows contain coins or not.

The bodily rearward sliding of the stacks of coin in the act of inspection described in connection with Fig. 8, is enabled when the plurality of fillers 16 at one end of the box, as illustrated in Fig. 4, is removed. These 120 fillers consist of a wooden strip, or more if desired, and a plurality of stiff paper pieces, the idea in the use of the fillers being that after the requisite number of coins are packed in place, the remaining empty space 125 is suitably filled in so as to keep the coins from sliding around in the box.

Other methods of packing the coins are

illustrated in Figs. 6 and 7. In Fig. 6 the paper ribbon described in connection with Fig. 9 is again employed, but this time in conjunction with a rather thick mat 17 which lies on top. This mat readily accommodates itself to unevenness in the top surface of the coins when packed in place, crushing the projecting parts of the paper ribbon, filling out the hollow places and packing tightly over the high places when the lid is affixed. In Fig. 7, small lateral partition pieces or spacers 18 are inserted between each pair of stacks of coins as it is packed in the box. When the mat 17 is used in connection with these spacers, the rather stiff projecting edges sink into the under side of the mat, conveniently defining compartments from which the coins cannot escape.

Of course this latter method requires more time in being carried out, but it does keep the coins from sliding off at the top of the stack. The separators 13, 14 are used in connection with all methods of packing because the feature of inspection is carried out or rather desired to be carried out, regardless of what the method of packing is.

In Fig. 10, provision is made for preventing the bottom of the box from sagging in case it should exhibit a tendency to do so. The simple expedient of a screw bolt 19 is here employed, being connected between the top 5^a and the bottom of the box 1.

In disbursing the coin

any one, that is to say desired one, of the plurality of removers or scrapers, 15, 15^a in Figs. 12, 14 and 15 and Figs. 11 and 13, may be used. The remover 15^a, which is illustrated in use in Fig. 11, is so cut or graduated in use in Fig. 11, is so cut or graduated that any desired number of stacks of coins up to \$1.00, considering for example that the box there shown is filled with pennies in stacks of 25 each, can be removed.

When the broadest portion is inserted behind the foremost row of coin, four can be shoved forwardly, or in other words, removed. But before this can be done, it is necessary to break the intertwining paper ribbon 11 which is perforated at intervals as at 11^b. Should it be desired to remove three stacks that portion of the remover extending out at right angles and designated with the mark "3," is employed. Or if only one stack is to be removed, then that portion extending straight up is employed. Stacks are also easily removed by pulling the free end of the ribbon.

Provision is not made for the removal of two rows since obviously the portion for the removal of one row can be used twice, but if it may be desired, the remover 15^a can be provided with an extension wide enough for the removal of two rows at a time. The reader can easily understand, without fur-

ther extensive explanation at this time, how 65 the various removers are used to remove rows of stacks of coin. The disbursing officer is supposed to have a supply of these graduated removers on hand, and repeated use and methodical or orderly arrangement 70 of the instrument will train his hand so that he can instantly pick up the right remover so that he is enabled to slide the desired number of coin stacks forwardly in making a payment. 75

The mode of operation

may be briefly reviewed to advantage, but before proceeding, it is desired to point out in Fig. 11 that one edge of the box is stamped 80 with numerical designations 20 reading for example "2.50, 5.00, 7.50, 10.00, etc." Considering the box in this case, that is in Fig. 11, to contain pennies, the designations referred to will indicate to the disbursing officer what the value of the row of coins at the head of which the numerical designations stand, is.

This feature alone is of great value because it enables the disbursing officer to 90 readily strike a balance at the end of the day's work. To illustrate: Suppose all of the rows of coins have been disbursed with the exception of the last three, that is to say, the three rows nearest the closed end of 95 the box. If all three rows are intact, he need simply glance at the numerical designation on the flange and see that the amount of coin left in the box is to the value of \$7.50. Or if the third row has been broken and four stacks taken out, he can simply deduct \$1.00 from the amount designated on the flange and check up the box as containing \$6.50. The designations 20 will of course vary according to the particular kind 100 of coins which the box contains. If it be gold pieces, the designations will be correspondingly higher. 105

Now proceeding with the mode of operation. For purposes of convenience, a stand 110 or table 21 in Fig. 11 is provided. This stand has a ledge 22 along two edges to more securely hold or keep in place the tray 23 which is used in extension of the box 1. The end 4 of the box was removed previously to setting the coin box on the stand.

The disbursing officer is now ready to disburse the stacks of coin, and in doing so he employs the remover 15^a in the manner already fully pointed out above, sliding the various stacks of coins forwardly into the extension tray, and from there handing the money to the person who is entitled to it. There are times when the stand 21 is not desired to be employed and in such cases 120 a smaller stand 24 in Fig. 2 is used. This stand stands at a slight angle and is only 125 large enough to hold the coin box itself.

While the construction and arrangement of the improved coin handling and containing method and means as herein described and claimed, is that of a generally preferred form, obviously modifications and changes may be made without departing from the spirit of the invention or the scope of the claims.

I claim:—

10. 1. A coin container, comprising a box into which stacks of coin are packed, and stack separating means arranged to be crushed down on the various stacks to provide keepers preventing coins from high stacks sliding over on lower stacks.
15. 2. A coin container, comprising a box, a ribbon of suitable material threaded around stacks of coins as they are packed into the box, said ribbon being broader than any stack is high; and a lid securable on the box and crushing down the exposed upstanding portion of the ribbon to form keepers preventing coins from high stacks sliding onto adjacent lower stacks.
20. 3. A coin container, comprising a box, a paper or other suitable ribbon twined around stacks of coins as they are packed into the box, said ribbon being broader than any stack is tall; a lid, with means by which it
25. 30. is secured on the box, crushing down the exposed upstanding portions of the ribbon to form keepers preventing coins from sliding

off higher stacks onto adjacent lower stacks; and double spacers between rows of coins, one being slightly higher than the other to 35 enable the introduction of an instrument for shoving back preceding coin rows so that the row in front may be inspected for intactness.

4. A coin container, comprising a box, a ribbon of suitable material threaded around 40 stacks of coins as they are packed into the box, said ribbon being broader than any stack is high, a lid securable on the box, and a mat interposed between the lid and coin stacks crushing down the exposed upstanding portions of the ribbon.

5. A coin container, comprising a box into which rows of coin stacks are packed, separating means running in both directions between pairs of the stacks, a lid securable on 50 the box, and a mat interposed between the lid and coin stacks coacting with the separating means to isolate the stacks in compartments.

6. A coin container, comprising a box into 55 which stacks of coins are packed, means applied to the coin stacks providing a separation and projecting slightly thereabove, a lid securable on the box to crush the projecting ends over the stack, and means between the 60 lid and bottom of the box preventing sagging of the bottom and a consequent looseness between the lid and said crushed portion.

STEPHEN JOSEPH BRUNE.
